UNITED STATES PATENT OFFICE.

DILMAN SNYDER BOWMAN, OF KITCHENER, ONTARIO, CANADA.

STOVEPIPE.

1,249,312.

Specification of Letters Patent. Patented Dec. 11, 1917.

Application filed March 16, 1917. Serial No. 155,274.

To all whom it may concern:

Be it known that I, DILMAN SNYDER BOWMAN, a subject of the King of Great Britain, residing at Kitchener, in the Province of Ontario, Dominion of Canada, have invented 5 certain new and useful Improvements in Stovepipes, of which the following is a specification.

This invention relates to improvements 10 in stove pipes, and the objects of the invention are to facilitate governing the draft which is supplied to stoves, to permit of the stove pipe being utilized for the ventilation of the room in which it is placed, and generally to adapt the several parts to better 15 perform the functions required of them.

With these and other objects in view, the invention consists essentially of the improved construction particularly described 20 and set forth in the following specification and accompanying drawings forming part of the same.

In the drawings:

Figure 1 is a side elevation of a length of 25 stove pipe embodying my invention.

Fig. 2 is a vertical section of the same showing the several dampers located therein.

Fig. 3 is an enlarged plan view of my device with the elbow 10 removed.

Fig. 4 is a perspective view of the dampers.

Like characters of reference refer to like parts in the several figures.

Referring to the drawings, A represents a 35 length of stove pipe provided intermediate of its length with an air inlet or ventilating pipe 10. The pipe A is designed to house a plurality of dampers 11 provided with radially extending slots 12 designed to embrace 40 the vertical rod 13, which is pivotally attached by means of the brackets 14 to the said dampers.

In the embodiment illustrated three dampers are shown, and the middle one is provided 45 with a spindle 15 extending diametrically thereacross, and which extends through the walls of the pipe A, to which it is secured by the nut 16.

That end of the spindle remote from the 50 nut 16 is formed with finger grips as shown at 17, and a washer 18 is slidably mounted

on the spindle and designed to co-act with the spiral spring 19 located between the said washer and finger grip.

The several dampers are equidistantly 55 spaced and the upper and lower dampers are pivotally supported by the spindles 20 which extend diametrically across the lower face and are pivotally supported by the walls of the pipe A, each of the dampers 60 being further provided with a pair of orifices 21 located diametrically opposite each other, but arranged in such a manner that when the dampers are horizontally disposed, 65 that no two orifices will be arranged in alignment.

It will be apparent that while there will be sufficient draft through the orifices 21 in the dampers, the cold air entering the flue 10 will mix with the hot air gases and smoke 70 from the stove, to provide an afterburning of the products of combustion. In this way complete combustion is obtained without extra cost of fuel.

The air in the surrounding atmosphere 75 will also be kept in good circulation by means of the ventilating pipe 10, and in fact there will be a constant current of air passing through it to be heated, thus securing an even temperature.

When a stove fitted with this device is in 80 operation, and it is found necessary to regulate the drafts, the spindle 15 is rotated through the medium of the finger grip 17, and all the dampers 11 are simultaneously 85 rotated through the medium of the vertical rod 13.

As many changes could be made in the 90 above construction, and many apparently widely different embodiments of my invention, within the scope of the claim, constructed without departing from the spirit or scope thereof, it is intended that all matter contained in the accompanying specification and drawings be interpreted as illustrative, and not in a limiting sense.

What I claim as my invention is:

A new article of manufacture comprising 100 a stove pipe section, a reduced downwardly directed elbow carried by the upper part of the section above its middle line and communicating with the interior of the section

whereby the cool air from the room is fed to the pipe, equally spaced pivoted and perforated dampers in the section, one above the elbow and two below whereby the rising hot gases may be retarded before mixing with the cool air and whereby the subsequent mixture may be also retarded, the said perforations of each damper being so arranged that they will not be in alinement

when the dampers are closed, and means for 10 simultaneously actuating all the dampers.

In witness whereof I have hereunto set my hand in the presence of two witnesses.

DILMAN SNYDER BOWMAN.
